UNITED STATES PATENT OFFICE.

ALBERT J. ALLISON, OF DAYTON, OHIO, ASSIGNOR TO THE A. A. SIMONDS SONS COMPANY, OF DAYTON, OHIO, A CORPORATION OF OHIO.

ROLL FOR BEATING-ENGINES.

1,273,982.

Specification of Letters Patent. Patented July 30, 1918.

Application filed May 3, 1917. Serial No. 166,102.

To all whom it may concern:

Be it known that I, ALBERT J. ALLISON, a citizen of the United States, residing at Dayton, in the county of Montgomery and State 5 of Ohio, have invented certain new and useful Improvements in Rolls for Beating-Engines, of which the following is a full, clear, and exact description.

My invention relates to means for clamping 10 the fly bars on the rolls of heating engines used in paper pulp mills. A beating roll usually consists of a cylindrical core, mounted on a shaft on which the roll is carried and by which it is rotated. On this roll a large 15 number of plates, called fly bars, are clamped, alternating with strips of wood. The bars are arranged parallel to the axis and radiate from the roll. The intervening wood strips are considerably narrower radially than the bars, and when completed 20 the roll presents a plurality of radiating, longitudinal steel blades. Until now it has been customary to secure the fly bars to the roll with a metal ring or hoop at each end 25 of the roll. These were put on red hot and when they contracted drew the fly bars down tightly to the core. One objection to this method is the difficulty of getting the bars off when necessary, and the possibility that 30 when the bars are renewed, which often has to be done in the field by unskilled labor, the rings are not properly shrunk on again. Another objection is that a slight difference in the size of a bar; the bar being a little too 35 narrow, for example, prevents this bar from being clamped by the ring. Or a bar which is too broad may prevent the ring clamping bars on each side of it. In operation these bars have to coöperate with a group of sta- 40 tionary bars and one or more loose fly bars in a roll may result in injury to the parts and consequent delay and expense.

The object of my invention is to overcome the difficulties mentioned, at the same 45 time providing for inequalities in the parts, so that in case the bars are not uniform in width, which is quite likely to be the case, they will still be securely clamped to the core.

50 In the accompanying drawings:

Figure 1 is an elevation of my improved beater roll, partially sectional, showing the clamping rings in place ready to be drawn together for the purpose of clamping the fly bars to the coil.

Fig. 2 is a similar view, with the rings drawn to place, showing the effect upon the tongues of the fly bars.

Fig. 3 is an end view of the roll with the clamping ring removed, showing the alternate arrangement of the fly bars and wood strips.

Fig. 4 shows a modification; a different way of forcing the rings into place.

Like numerals refer to similar parts in all 65 of the views.

The cylindrical core 10 is mounted on a shaft 11 in the ordinary or any suitable manner. At each end the core is slightly tapered, as at 12-12. The fly bars 13 are broad, relatively thin plates approximately the length of the core and at each end of the bars are notched as at 14, leaving projecting tongues 15. In their normal state the inner edges of the bars are rectilinear, and therefore there 70 is a space beneath the tongues formed by the taper of the core. The wood strips 16, which alternate with the bars also have notches, 17, in their ends.

A ring 20 is provided for each end of the 80 roll these rings having a tapered interior. In the preferred construction the rings are mounted on or made integral with circular disks 21. As seen in Fig. 1 the rings are of such diameter that their large ends will just 85 start on the ends of the tongues 15 when the bars are in position around the core. By means of bolts which pass through the core the plates and rings are forced toward each other until they reach the position 90 shown in Fig. 2. In this figure it is seen that the tongues have been deflected inward by the taper of the rings but that there remains some space between the tongues and the beveled portions of the coil. In case of 95 inequality in the width of the tongues some of them may be deflected more than others, but since considerable force is necessary to secure even a slight deflection of the tongues it is clear that each of the bars is held firmly 100 against the core by the tension of its own tongues. When the bars require renewal it is only necessary to unscrew the nuts and remove the rings, which can be done with a few blows of a hammer.

105 In the modification shown in Fig. 4 the plates are forced toward each other by large nuts screwed on the shaft, which is threaded for the purpose. Other modifications are possible without departing from the spirit 110

of the invention or exceeding the scope of the appended claims.

What I claim is as follows:

1. A beater roll, comprising a cylindrical core, the end of which is slightly tapered, a plurality of fly bars arranged around the core, each bar having a tongue which extends over the tapered portion of the core, a ring adapted to encircle the tongues, said ring having a tapered interior whereby when it is forced axially with reference to the core the tongues are drawn toward the axis of the core, the space beneath the tongues afforded by the taper of the core permitting more or less deflection of the tongues, so that each bar is clamped against the core by the tension of its own tongue; and means for forcing the ring exially.
2. A beater roll, comprising a cylindrical core, each end of which is slightly tapered, a plurality of fly bars arranged around the core, the bars having at each end tongues which extend over the tapered portions of the core, a pair of rings adapted to encircle the tongues, said rings having tapered interiors whereby as the rings are forced toward each other the tongues are drawn toward the axis of the core, the space beneath the tongues, afforded by tapering the core, permitting more or less deflection of the tongues, so that each bar is clamped against the core by the tension of its own tongues; and means for forcing the rings toward each other.
3. A beater roll, comprising a cylindrical core, each end of which is slightly tapered, a plurality of fly bars arranged around the core, the bars having at each end tongues which extend over the tapered portions of the core, a pair of rings adapted to encircle the tongues, said rings having tapered in-

teriora whereby as the rings are forced toward each other the tongues are drawn toward the axis of the core, the space beneath the tongues, afforded by tapering the core, permitting more or less deflection of the tongues, so that each bar is clamped against the core by the tension of its own tongues, circular plates on which the rings are mounted, and bolts which pass through the plates and through the core whereby the plates and rings are drawn toward each other.

4. A beater roll, comprising a cylindrical core, each end of which is slightly tapered, a plurality of fly bars and strips of wood arranged alternately around the core, the bars having at each end tongues which extend over the tapered portions of the core, a pair of rings adapted to encircle the tongues and ends of the wood strips, said rings having tapered interiors whereby as the rings are forced toward each other the tongues are forced toward the axis of the core, the space beneath the tongues, due to tapering the core, permitting deflection of the tongues, so that each bar is clamped against the core by the tension of its own tongue; and means for forcing the rings toward each other.

5. A beater roll, comprising a core, fly bars arranged around said core and resilient means for clamping the bars thereto.

6. A beater roll, comprising a core, fly bars arranged around said core and means for employing the resiliency of portions of the bars themselves for clamping the bars against the core.

In testimony whereof I affix my signature in the presence of two subscribing witnesses.

ALBERT J. ALLISON.
